(57) **CLAIM**

The ornamental design for a window frame component as shown and described.

DESCRIPTION

FIG. 1 is a perspective view of a window frame component of a first embodiment of our new design.

FIG. 2 is a first end view of the window frame component of FIG. 1.

FIG. 3 is a second end view of the window frame component of FIG. 1.

FIG. 4 is a first side elevation view of the window frame component of FIG. 1.

FIG. 5 is a second side elevation view of the window frame component of FIG. 1.

FIG. 6 is a top plan view of the window frame component of FIG. 1.

FIG. 7 is a bottom plan view of the window frame component of FIG. 1.

FIG. 8 is a perspective view of a window frame component of a second embodiment of our new design.

FIG. 9 is a first end view of the window frame component of FIG. 8.

FIG. 10 is a second end view of the window frame component of FIG. 8.

FIG. 11 is a first side elevation view of the window frame component of FIG. 8.

FIG. 12 is a second side elevation view of the window frame component of FIG. 8.

FIG. 13 is a top plan view of the window frame component of FIG. 8; and,

FIG. 14 is a bottom plan view of the window frame component of FIG. 8.

The uniformly-dashed lines illustrate portions of the window frame component that form no part of the claimed design. The drawings show a symbolic break comprised of dot-dashed lines in FIGS. 1, 4-8 and 11-14. The dot-dashed break lines, as well as any portion of the article between the dot-dashed break lines, form not part of the claimed design.
